(57) **CLAIM**

The ornamental design for a digital camera, as shown and described.

DESCRIPTION

FIG. 1 is a front, top perspective view of a digital camera, showing my new design;

FIG. 2 is a rear, top perspective view thereof;

FIG. 3 is a front, bottom perspective view thereof;

FIG. 4 is a front view thereof;

FIG. 5 is a rear view thereof;

FIG. 6 is a left side view thereof;

FIG. 7 is a right side view thereof;

FIG. 8 is a top plan view thereof; and,

FIG. 9 is a bottom plan view thereof.

The elements shaded in a transparent grey wash, and surrounded by broken lines are included for the purpose of illustrating portions of the digital camera and forms no part of the claimed design.
